SHEARS

Albert D. Brison, Detroit, Mich.

Application March 18, 1938, Serial No. 196,735

3 Claims. (Cl. 30—341)

My invention relates to a new and useful improvement in a shears adapted primarily for use as a barber's shears. The shears commonly used by the barber comprises a pair of pivotally mounted blades and experience has shown that through repeated operation of the shears a cramping of the operator's hand and wrist is frequently effected. This is due to the fact that in the operation of the shears it is necessary to bring the thumb and the finger into close relation to each other in the cutting movement. There are operations, however, in which it is necessary that the thumb and the finger be brought into close relation to each other in order to permit the proper kind of hair cut and in order to properly operate on the hair.

It is an object of the present invention to provide a shears so constructed and arranged that the same may be operated by the operator without requiring a close approach of the thumb to the finger while at the same time the shears may also be operated when the thumb is brought into close approach to the finger. In this way a shears is constructed in which the undesirable cramping of the hand is practically eliminated while at the same time a proper operation of the shears may be effected.

Another object of the invention is the provision of a shears having an angularly turned shank on one of the blades carrying a pair of loops or thumb receiving portions positioned closely together and directed angularly outwardly therefrom.

Another object of the invention is the provision of a shears of this class which will be simple in structure, economical of manufacture, durable, compact and highly efficient in use.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a perspective view of the invention.

Fig. 2 is a plan view of the invention.

As shown in the drawing, these shears comprise a pair of blades 7 and 8 pivotally connected together by means of the screw 9. Extending outwardly and formed integral with the blade 7 is the shank 10 on the end of which is formed the loop or eyelet 11 for reception of a finger of the hand. Extending outwardly from the loop 11 is the curved finger grip 12. In use one of the fingers is projected through the loop 11 and

another finger engages against the concave side of the member 12. It will be noted that the shank 10 extends substantially in alignment with the blade 7 and forms a direct continuance thereof. A shank 13 extends outwardly from the end of the blade 8 and this shank 13 is also formed integral with the blade 8. The shank 13, however, does not extend in alignment with the blade 8 but is turned outwardly therefrom to extend angularly thereto. Formed on the end of the shank 13 so that the diameter thereof coincides with longitudinal medial line of the shank 13 is a thumb receiving loop or eyelet 17. Secured to this eyelet 17 and projecting inwardly therefrom but on a line extended angularly to the longitudinal axis of the shank 13 is a thumb receiving loop 15. This location of the loop 13 is clearly brought out in Fig. 2. It will be noted that the outer end of the loop 15 is positioned beyond the outer end of the loop 17 and the common diameter of these loops would not extend at right angles to the longitudinal axis of the shank 13 but would be extended at an acute angle thereto.

When the shears are used for hair-cutting the operator would engage his thumb in the outer loop, that is, in loop 17, throughout the major portion of the operation of hair-cutting. This would enable the operator to open and close the blades 7 and 8 without causing the thumb to move into close approach to the fingers one of which would be projected through the loop 11. Experience has shown that it is when the thumb is brought into close approach to the fingers that the strain on the wrist muscles and the cramping of the fingers and hand is effected. In using the present invention the operator would place his thumb in the loop 17 and when so placed, the thumb would not be brought into close approach with the fingers when the blades are being closed and thus the fatigue incident to cutting operations would be avoided. During certain operations in hair-cutting, however, it is necessary that the thumb be brought to close approach to the fingers of the operator's hand; this portion of the operation is commonly referred to as "shingling." When performing this part of the hair-cutting operation, the operator would, of course, project his thumb through the loop 15. Consequently, the shears constructed as illustrated are adapted for use in the same manner as, and to perform all of the operations of, the ordinary shears while at the same time provision is made to relieve the operator of the strain commonly encountered.

While I have illustrated and described the preferred form of construction, I do not wish to limit myself to the precise details of structure shown, but desire to avail myself of such variations and modifications as may come within the scope of the appended claims.

What I claim as new is:

1. A shears of the class described, embodying a pair of blades pivotally connected intermediate their ends; a shank projecting outwardly from the end of each of said blades; a finger-receiving loop on the end of one of said shanks; a thumb-receiving loop on the end of the other of said shanks; an auxiliary thumb loop positioned between the finger loop and the thumb loop and secured to the thumb loop for spacing the thumb loop and the finger loop apart while permitting complete cooperation of said blades.
2. A shears of the class described, embodying a pair of blades pivotally connected intermediate their ends and swingable into overlapped relation upon movement of said blades to closed position; a shank projecting outwardly from the end of each of said blades; a finger-receiving loop on

the end of one of said shanks; a thumb-receiving loop on the end of the other of said shanks; an auxiliary thumb loop positioned between said finger loop and said thumb loop and secured to said thumb loop and engageable with said finger loop upon movement of said blades to closed position. 5

3. A shears of the class described, embodying a pair of blades pivotally connected intermediate their ends and swingable into overlapped relation upon movement of said blades to closed position; a shank projecting outwardly from the end of each of said blades; a finger-receiving loop on the end of one of said shanks; a thumb-receiving loop on the end of the other of said shanks; an auxiliary thumb loop positioned between said finger loop and said thumb loop and secured to said thumb loop and movable toward said finger loop upon closing of said blades, said blades, upon closing movement, overlapping each other prior to engagement of said auxiliary thumb loop with said finger loop. 10 15 20
